PICKUP TONGS

Frank C. Barr, Morgantown, W. Va.

Application June 29, 1950, Serial No. 171,210

3 Claims. (Cl. 294—106)

1

This invention relates generally to tongs and more particularly to a wand having at one end a pair of tongs with dual actuating jaws operated by depressing an actuator at the other end of the wand.

Pickup tongs usually have one stationary jaw and a movable jaw pivoted thereto. Usually the stationary jaw is one end of the wand and the other end carries a lever connected to actuate the movable jaw. A tong having a single actuating jaw provides difficulty in picking up articles. The article is rolled or turned over by the movable jaw to bring it into engagement with the stationary jaw. This makes it difficult to handle the articles being picked up and results in a waste of time. Frequently after the articles are rolled out of position by the movable arm they are more difficult to retrieve. It is sometimes undesirable to disturb an article to be picked up, it should be carefully grasped and set in the place intended. This is difficult to achieve with a stationary jaw cooperating with a movable jaw.

The tongs comprising the present invention have complementary jaw members, each of which are actuated to move in unison by reason of the fact that they are provided with intermeshing gear segments. An operating trigger is connected to actuate one jaw member and the other moves in unison to converge on an article and pick it up. Since both jaw members approach and grasp the article it remains undisturbed save for lifting it and depositing elsewhere.

Simultaneously converging jaws permit the tongs to pick up large, as well as small, articles which is difficult, if not impossible, with tongs having only one movable jaw.

These and other advantages appear herein-after in the following description and claims.

The accompanying drawings show for the purpose of exemplification without limiting the invention or claims thereto a practical embodiment illustrating the principles of this invention wherein:

Fig. 1 is a vertical sectional view showing a pair tongs and the actuating member.

Fig. 2 is a vertical elevation.

Fig. 3 is an enlarged detail view of the trigger actuating mechanism as cut from a piece of sheet metal.

Fig. 4 is a perspective view of the trigger after being shaped by folding into assembled relation.

Referring to Fig. 1 of the drawings the pair of tongs is made of a tubular wand member 1 which may be flattened at its lower end, as indicated at 2, to provide a bearing section 3 for

2

receiving the jaw members 4 and 5. The jaw members 4 and 5 are pivotally supported on the pins 6 and 7 that pass through the flattened bearing portion of the wand. Each jaw member is preferably made up of fingers such as illustrated at 8 in Fig. 2 extending from a body section. The body section of each jaw member has a gear segment as shown at 10 and 11 in Fig. 1. A gear segment 10 of the jaw member 4 is in mesh with the gear segment 11 of the jaw member 5.

The jaw member 5 has an upwardly extending arm 12, preferably integral therewith, having a hole in the top thereof to pivotally receive the end of the actuating rod member 13. The other or upper end of the rod member 13 passes through the slot 14 in the trigger 15 as shown in Figs. 1 and 4 and extends slightly therebeyond. The rod 13 has a reduced section 16 which may be slipped into the slot 14 of the trigger and allows very little play therebetween. The reduced section 16 merely functions to pivotally connect the rod relative to the trigger.

A spiral spring member 17 has one end stepped 25 into the cap 18 that closes the top of the wand 1. The other end of the spring extends over the upper end of the actuating rod 13 and bears against the end or face 20 of the trigger 15 to apply pressure and maintain the trigger in an extended position. The pressure of the spring 17 forces the rod 13 downwardly which rotates the lever 12 in a counterclockwise direction and thereby opens the fingers of the jaw members 4 and 5 as shown in Fig. 1.

The trigger 15 is made from a single sheet of material, as illustrated at 21 in Fig. 3, which is provided with the side members 22 and 23 and the end extensions 24 and 25. When folded along the dotted lines the trigger member 15 takes the shape of such as shown in Fig. 4 with the sides 22 and 23 being in spaced relation to each other in the form of the sides of a box. The end 24 extending beyond the trigger is bent over to form the hook 26 which is inserted 30 through the small opening 27 of the wand and hooked over the bar 30 formed by this opening. The trigger 15 extends through the large opening 28 and the lower end of the trigger has the stop member 25 extending beyond the end of the opening 28 to form a stop to limit the outer extension of the trigger 15 from the wand. Thus, the hook 26 extending through the opening 27 around the bar 30 of the wand provides the hinge for the trigger. The inward movement of the trigger is limited by the walls of the wand and

one may press the trigger to its full extent. The outward extension of the trigger is limited by the stop 25. This very simple structure provides an economical mechanism for actuating the tongs and is in itself a very important object and feature of this invention. The hooked hinged member 26 maintains the upper end of the trigger in the opening 28 at all times. Thus, the trigger 15 never becomes fouled and is not likely to cause misoperation of the tongs.

By depressing the trigger 15 the end 20 carrying the opening 14 moves the actuating rod 13 upwardly to swing the jaw member 5 in a clockwise direction thereby forcing the fingers 8 toward one another to grasp an article. At the same time the spring 17 is compressed to a greater degree, and when the trigger is released the spring 17 returns the jaws to their open position.

I claim:

1. A pair of tongs comprising a tubular wand, a pair of jaw members each having complementary gear segments and an article gripping portion, pin means mounted on said wand adjacent one end thereof to pivotally support the jaw members with their gear segments in mesh with each other and their grasping portions co-operating when contracted, an arm on one jaw member extending beyond the other side of the pin means from its gripping portion, an operating trigger member pivotally mounted adjacent the other end of the wand, a rod connecting the operating trigger member and said arm, and spring means co-operating with said operating trigger member to maintain said jaw members in their open position.
2. A pair of tongs comprising a tubular wand, a pair of jaw members each having complementary gear segments and an article gripping

portion, pin means mounted on said wand adjacent one end thereof to pivotally support the jaw members with their gear segments in mesh with each other and their grasping portions co-operating when contracted, an arm on one jaw member extending beyond the other side of the pin means from its gripping portion, a trigger member mounted for movement in a slot in the wand, a hook on the upper end of the trigger extending over a bar carried by the wand to provide a hinge therefor, a stop extending from the lower end of the trigger to engage in the wand and limit its extension therefrom, a rod connected at one end to said arm and having a seat adjacent its other end pivotally connected to said trigger, and a spring seated at the upper end of the wand and engaging against said trigger to extend it outwardly forcing the rod to open the jaw members.

3. A trigger comprising a sheet of material folded to provide a box-shaped member having a narrow side connected with wide flat sides along their adjacent marginal edges, the fourth side opposite the narrow side being open, a hook extending from said narrow side to form a hinge, a stop projection extending from one corner of each wide side diametrically opposite from said hook, and a seat in the other narrow end adjacent said hook for receiving an actuating member.
